UNITED STATES PATENT OFFICE

JOSEPH ORTEN GADD, OF WALLINGFORD, CONNECTICUT, ASSIGNOR TO R. WALLACE & SONS MANUFACTURING COMPANY, OF WALLINGFORD, CONNECTICUT, A CORPORATION

ROTARY-CUTTER CAN-OPENER

Application filed October 5, 1929. Serial No. 397,483.

This invention relates to an improvement in can-openers and particularly to can-openers of the rotary-cutter type.

One of the main objects of this invention is to provide a simple and reliable rotary-cutter can-opener constructed with particular reference to facilitating the rotary movement of the cutter to minimize the effort required to operate the can-opener.

10 A further object of this invention is to provide a can-opener of the type referred to in which the tendency of the cutter to ride upward upon the rim of the can is minimized.

With the foregoing and other objects in view, my invention consists in a rotary-cutter can-opener having certain details of construction and combinations of parts as will be hereinafter described and particularly recited in the claims.

20 In the accompanying drawings:

Fig. 1 is a face view of a rotary-cutter can-opener embodying my invention, the partial outline of the top of a can being indicated by broken lines;

25 Fig. 2 is a broken edge view thereof;

Fig. 3 is a view looking toward the pivot end thereof;

Fig. 4 is an enlarged-scale broken view partly in elevation and partly in section, illustrating the application of the can-opener to a can;

Fig. 5 is a perspective view of the rotary-sleeve detached, prior to the application of the rotary-cutter thereto and the formation 35 of the retaining-flange;

Fig. 6 is a face view of the rotary-cutter detached; and

Fig. 7 is a view thereof in edge elevation.

In carrying out my invention as herein shown, I employ a disk-like plano-convex rotary-cutter 10 having a convex outer face 11 for engagement, adjacent its axial bearing-passage 12, with the inner face of the rim 13 of a can 14 and also having a flat complementary inner face 15. The edge of the rotary-cutter is beveled off in the usual manner to provide a sharp peripheral cutting-edge 16 and it is provided with the axial bearing-passage 12 aforesaid, which is adapted to rotate 45 upon an annular bearing-surface 17 formed

upon the periphery of a sleeve 18. The said bearing-passage 12 is larger in diameter than the bearing-surface 17 to permit the rotary-cutter 10 to have slight rocking movement with respect to the sleeve 18 for the purpose 55 as will hereinafter appear.

The cutter 11 has rotary, rocking and limited endwise movement upon the bearing-surface 17 of the sleeve 18 and is held in place against displacement by a retaining-flange 19 60 formed at the inner end of the said sleeve and by an annular limiting-shoulder 20 formed about midway the length of the sleeve and terminating at its outer end in a peripheral bearing-surface 21 larger in diameter than the bearing-surface 17 and adapted to rest upon the upper edge of the rim 13 of the can 14 or similar article, as shown in Fig. 4 of the drawings.

The outer end of the sleeve 18 opposite the retaining-flange 19 is formed with an annular guide-flange 22 projecting outward from the bearing-surface 21 aforesaid and virtually creating, between its inner face and the adjacent convex outer face of the cutter 10, 70 an annular guide-groove 23 for the reception of the rim 13 of the can 14 aforesaid.

The sleeve 18 is mounted for both rotary and axial sliding movement upon a rod-like shank 24 formed at its inner end with a longitudinal cutaway portion 25 for the reception of an end-plate 26 secured to it by means of rivets 27.

The end-plate 26 just above referred to is provided at a point axially in line with the shank 24 with an offsetting sharp-ended prong or pivot 28 arranged parallel therewith and adapted to be forced through the center of one end of a can in the customary manner of such can-openers.

90 The end-plate 26 is also formed with a hook-like projection 29 for the removal of bottle-caps and at its opposite side with a tang 30 extending substantially parallel with the shank 24 from which it is spaced by a clearance-notch 31. The inner edge of the said tang 30 is provided with a sharp edge 32 for opening cans in the usual manner of lever-type can-openers if such procedure is desired.

The end of the shank 24 opposite the pivot 28 is provided with a handle 33 by means of which my improved can-opener may be employed for opening cans by means of the rotary-cutter 10 or by means of the cutting-tang 30 or for removing bottle-caps by means of the hook 29, as may be elected.

In the use of my improved can-opener, the pivot or prong 28 is forced through the center of one end of a can, after which the sleeve 18 is slid along the shank 24 until the guide-groove 23 is in line with the rim 13 of the can 14, at which time downward pressure is applied upon the handle 33, with the effect of 10 causing the cutting-edge 16 of the rotary-cutter 10 to penetrate the end of the can at a point adjacent the inner face of the rim 13 to an extent sufficient to bring the bearing-surface 21 in engagement with the upper end 15 of the said rim, as shown in Fig. 4 of the drawings.

The cutter is now rolled edgewise by swinging the handle 33 around the can, with the effect of causing the said cutter to sever the 20 top of the same in the usual manner of can-openers of the rotary-cutter type.

Now insofar as the sleeve 18 is free to rotate upon the shank 24 and the cutter 10 is free to rotate upon the said sleeve it will be 25 seen that each may have a different speed of rotation as is required to have each of them make a rolling contact with the portions of the can with which they engage. Thus the sleeve 18, owing to the fact that its bearing-surface 21 is smaller in diameter than the 30 cutter 10, will roll much faster than the latter, which is a condition requisite to smooth and easy cutting.

By convexing the outer face 11 of the 35 cutter 10, the cutting-edge 16 of the same is maintained out of contact with the inner face of the rim 13, so that there is no appreciable tendency for the cutter to jam or ride up upon the said rim, as has been the case 40 when the edge of the cutter has been permitted to engage the inner face of the rim 13.

Furthermore, by arranging the cutter 10 so that it is free for limited oscillating movement, any unevenness in the can is compensated for, such, for instance, as the vertical seam in the can, which causes a bulge 50 in the rim.

I claim:

1. A can-opener comprising a cylindrical 55 shank provided at its opposite ends respectively with a handle and a pivot; a rotary-sleeve mounted upon the said cylindrical shank; and a disk-like cutter mounted upon the said sleeve with capacity for both independent rotation and lateral rocking movement with respect thereto; whereby the said cutter and sleeve may have differential rotary as well as rocking movement to facilitate 60 the opening of a can.

2. A can-opener comprising a cylindrical 65

shank provided at its opposite ends respectively with a handle and a pivot; a rotary-sleeve mounted upon the said cylindrical shank; and a disk-like cutter mounted upon the said sleeve with capacity for both independent rotation and lateral rocking movement with respect thereto.

3. A can-opener comprising a cylindrical shank provided at its opposite ends respectively with a handle and a pivot; a rotary-sleeve mounted upon the said cylindrical shank and formed with a peripheral bearing-surface flanked by a complementary pair of limiting-shoulders; and a disk-like rotary-cutter thinner than the distance between the 70 limiting-shoulders of the said sleeve and provided with an axial bearing-passage 75 appreciably larger in diameter than the said bearing-surface for free rotation and lateral rocking movement thereon between the said 80 limiting-shoulders.

In testimony whereof, I have signed this specification.

JOSEPH O. GADD.
